UNITED STATES PATENT OFFICE.

NEHEMIAH SLEEPER, OF BURLINGTON, NEW JERSEY.

DESIGN FOR BOTTLE.

Specification forming part of Design No. 5,401, dated December 5, 1871.

To all whom it may concern:

Be it known that I, NEHEMIAH SLEEPER, of Burlington, in the county of Burlington and State of New Jersey, have invented or produced a Design for a Bottle, of which the following is a specification:

The nature of my design is fully represented in the accompanying drawing, to which reference is made; and the figure in which shows a side view of a bottle, A being the neck, B the curved shoulder, and D the body.

From the point *x* in the neck below the mouth *y* to the point *m* the vessel is made polygonal, the lines *n n n*, &c., indicating the edges of the sides of the polygon, and these edges are united by a series of arcs of circles, *w*, where the polygonal portion of the neck meets the cylindrical

portion *t* of the same. The lines *u* terminate below where the polygonal portion of the body meets the cylindrical portion of the same at the zigzag belt *f*, which surrounds the bottle, each line terminating at the apex of one of the numerous cones formed by the belt.

I claim—

The design for a bottle, substantially as described and illustrated.

In testimony whereof I have signed my name to this specification in the presence of two subscribing witnesses.

NEHEMIAH SLEEPER.

Witnesses:

WM. A. STEEL,
HARRY SMITH.
